James Robert Dailey, Kokomo, Ind., assignor to
Turner Manufacturing Company, Kokomo,
Ind., a corporation of Indiana

Application June 17, 1948, Serial No. 147,018

Term of patent 3½ years

(Cl. D14—30)

To all whom it may concern:

Be it known that I, James Robert Dailey, a citizen of the United States of America, residing at Kokomo, county of Howard, Indiana, have invented a new, original, and ornamental Design for a Wheel Balance Weight, of which the following is a specification, reference being had to the accompanying drawing, forming a part thereof.

In the drawing:

Fig. 1 is a front elevational view of a wheel balance weight, embodying my new design;
Fig. 2 is a bottom plan view thereof;
Fig. 3 is a rear elevational view thereof;
Fig. 4 is an end elevational view thereof; and
Fig. 5 is a top plan view thereof.

I claim:

The ornamental design for a wheel balance weight, substantially as shown.

JAMES ROBERT DAILEY.
